UNITED STATES PATENT OFFICE.

JOHN GRAHAM, OF LIVERPOOL, ENGLAND.

STOWAGE AND LAUNCHING OF SHIPS' LIFEBOATS.

Application filed June 15, 1922. Serial No. 568,436.

To all whom it may concern:

Be it known that I, JOHN GRAHAM, of 3 Mayfield Road, Grassendale, Liverpool, England, a British subject, have invented 5 certain new and useful Improvements in and Connected with the Stowage and Launching of Ships' Lifeboats, of which the following is a specification.

This invention has reference to the stow- 10 age and launching of ships' life boats for saving life at sea.

For a long time a requirement or regulation has existed that the number of boats to be stowed on board ship must be sufficient 15 to accommodate all the people on the ship and that the boats must be carried in such manner as to be capable of being readily launched from the ship in case of accident or foundering. Great difficulty has

20 been experienced in meeting this requirement and many attempts have been made to solve the problem with, however, only partial success. In fact, at the present time, the problem still remains and is constantly 25 before those of the mercantile marine world concerned with passenger ships (especially large ocean going passenger ships) it being generally admitted that the arrangements heretofore proposed fall far short of actual 30 requirements. Existing systems generally involve the stowage of two or more boats one upon the other under the same pair of davits as well as the stowage of a large number of 35 nested semi-collapsible boats on the ship, with the result, as is well known, of great difficulty (especially in connection with the recovery of the tackle for engaging with additional boats) and considerable loss of time 40 in launching. The semi-collapsible boats have also been found unsatisfactory in use.

It is also necessary that the stowing and launching gear be such that the boats can be launched individually or a number of them simultaneously as desired.

45 The object of this invention is to meet the aforesaid requirement by stowing a large number of boats in a special manner and without the necessity for nesting or for employing collapsible boats, the stowing, launching and chocking arrangement being 50 such that the boats can either be launched individually or a number of them simultaneously as desired.

According to this invention the boats are 55 all disposed, side by side, along the side of

the ship's boat deck with their longitudinal centre lines lying obliquely to the centre line of the ship, the boats lying together side by side in parallel formation and being retained in position by suitable chocks and 60 so that they can all be easily and quickly launched by suitable launching means.

As regards the disposition of the boats, the preferred arrangement is that wherein 65 the bow of one boat overlaps the stern of the adjacent boat, and in the case of the existing arrangement of ships' boat decks and deck houses, the bows of the boats will project, or overhang, the side of the deck, but the degree of this depends upon the angular 70 arrangement of the boats and the number desired to be stowed in a given deck side length.

The boats may be stowed on chocks, ar- 75 ranged parallel with the side of the ship, two chocks for each boat connected by a member adapted to receive the keel of the boat and to be inclined to the ship's centre line at the same angle as that of the centre line of the boat.

The launching means consist of single 80 vertical axis, swivelling, self-contained, independently-operated davits having a winding, or operating, gear upon same, capable of suspending the boat above its centre by a single tackle or rope, the vertical axis of the davit being placed near the side of the ship outboard of a line extending parallel to the ship's side through the center of the boats and in the space between each pair of 85 adjacent boats and relatively near the bow of the one boat, and the midships of the adjacent boat.

It will be seen that by this arrangement 90 effect is given to the marine regulation requiring the operator of power operated davits to be in such a position that he can observe and control the boat as it descends parallel with the ship's side.

The system of stowage of ships' boats under this invention is shown, by way of example, on the accompanying drawings, whereon:—

Fig. 1 is a plan view of part of a ship's 95 boat deck illustrating the known system of arranging ships' boats and one arrangement according to the present invention, and Figs. 2 and 3 are other views of part of a ship's boat deck with other arrangements under this invention. 100 105 110

Figs. 4 and 5, respectively, are perspective and plan views of one construction of chocks adapted to hold a ship's boat in position obliquely relatively to the centre line of the ship.

Referring to Fig. 1, the lower half illustrates a present known arrangement of ships' boats disposed parallel to the centre line of the ship's boat deck. With this arrangement it is possible to arrange seven boats *a* in line along one side of that part of the ship's boat deck shown in Fig. 1 and one boat *a*¹ against a deck house *b* with the necessary space between the same for manipulating and launching. It is found, however, that, with this arrangement, a sufficient number of ships' boats cannot be carried without nesting or banking the boats.

The upper half of Fig. 1 illustrates one arrangement under my invention wherein a number of ships' boats are arranged parallel to each other with sufficient space between each two adjacent boats for manipulating and launching. With this arrangement eleven boats *a* are shown as occupying a length of deck corresponding to that occupied by seven similar boats arranged in the old way and shown in the lower half of Fig. 1 while still affording them the same equal facilities for launching which, of course, is a very important matter as the extra boats would be of no avail in an accident if they could not be launched in time. It will be seen, in the arrangement shown in the upper half of Fig. 1, the bow or forepart of one boat overlaps the stern or rear part of an adjacent boat.

The ships' boats, arranged as in the upper half of Fig. 1, are stowed in position by means of any suitable chocking arrangement but, preferably, I employ, for each boat, a pair of chocks *c* connected by an oblique keel bar *d* as shown in Figs. 4 and 5 formed with a slot *d*¹ communicating with notches or recesses *c*¹ in the chocks *c* and adapted to receive the keel of the boat. The chocks *c* are so disposed relatively to the oblique keel bar *d* as to be parallel to the centre line of the ship's boat deck, and are spaced from each other so as to give proper accommodation for the boats. Chocks constructed and arranged in this manner provide a very efficient support for each boat. If desired, the slot *d*¹ may be formed in a part of the deck or any attachment thereto.

Each of the ship's boats *a* arranged according to this invention, and as shown in the upper half of Fig. 1, is preferably provided with a single davit *e* of the type known as the "Graham single davit" and adapted to rotate about a vertical axis for moving the boat from an inboard position to an outboard position as shown in dotted outline, left hand side of Fig. 1. The davits *e* have their axes located outboard of a line

extending parallel to the ship's side through the center of the boats when stowed. The arrangement shown is specially advantageous when manipulating and launching the boats, alternate boats being adapted to be dealt with simultaneously without any possibility of the persons dealing with one boat interfering with those dealing with the other boat. After launching the alternate boats in this manner the remainder can be despatched simultaneously. With such an arrangement the launching of ships' boats can be effected expeditiously without confusion and a much larger number of boats provided all ready for immediate use.

The arrangement shown in Fig. 2 is similar to that shown in the upper half of Fig. 1 with the exception that the angular disposition of the boats relatively to the centre line of the ship's boat deck is increased and a greater number of boats arranged in a corresponding length of ship's boat deck, more of each boat projecting over the ship's side than in the first arrangement.

In the arrangement shown in Fig. 3 the boats are somewhat differently disposed, the bows pointing in an opposite direction and a greater number are arranged in the same length of ship's boat deck than in Figs. 1 and 2. As compared with the existing arrangement, shown in the lower half of Fig. 1, the space formerly occupied by four boats is now occupied by nine or ten boats. One davit is provided, in this case, for each pair of adjacent boats, the davits being so disposed relatively to the chocks as to enable a boat on each side thereof to be connected, in turn, with the tackle on the davit. It is however, to be understood, that, if desired, a separate davit may be provided for each boat.

It will be understood that the construction of the chocks will vary according to the angular disposition of the boats, the keel bar *d* being disposed at a greater angle to the chocks according to the greater number of boats arranged on each side of the boat deck.

When a boat is to be lowered it is lifted by the davit hand gear off its chocks, and the davit swung round. A slewing movement of, say, about 120° is usually sufficient to bring the boat outboard parallel with the ship's side as the stowage of the boats is such that the boat normally lies partially turned towards the outboard position. In this way much time is saved when launching.

The angular disposition of the boats relatively to the centre line of the ship's boat deck enables the boats to be so arranged as to partly overhang the side of the ship and, in so overhanging in an oblique direction, it will be seen they do not offer a broad or flat surface to broken seas striking them; that is, the spray will strike them almost

bow on, and, therefore, they are not liable to be deranged or damaged as with existing arrangements.

Where substantial overhang of the boats occurs a hinged bracket may be fitted on the ship's side for each boat or for a number of boats and be adapted to support the bow thereof and prevent sagging.

The method of stowage herein described will, with normal passenger liners, permit a full equipment of class A lifeboats to be carried on the steamer, all separately arranged along the sides of the ship ready for use and, if desired, all attached to davits, without occupying practically any more deck space than that at present occupied by the doubled banking or nesting system.

Having now fully described my invention what I claim and desire to secure by Letters Patent is:—

1. In a ship the combination of ships' life boats that are stowed in parallel formation along the deck obliquely to the centre line of the ship and partly overhanging the ship's side, and davits of the single, vertical-axis, swivelling, self-contained, independently-operated type for launching the boats, a davit being located between two boats and also being located with its

vertical axis at or near the ship's side and outboard of a line extending parallel to the ship's side through the centres of the boats, so that the operator can observe the boat as it descends parallel with the ship's side. 35

2. In a ship the combination of ships' life boats that are stowed in parallel formation along the deck obliquely to the centre line of the ship and partly overhanging the ship's side, and davits of the single, vertical-axis, swivelling, self-contained, independently-operated type for launching the boats, davits located between pairs of boats and each davit being located with its vertical axis at or near the ship's side and outboard of a line extending parallel to the ship's side through the centres of the boats, so that by a movement of a davit about its axis through 120° the boat operated upon may be swung outboard into position to be 40 lowered into the sea parallel with the ship's side, the arrangement being such that the operator can observe the descent of the boat. 45

In testimony whereof I affix my signature in presence of two witnesses.

JOHN GRAHAM.
